UNITED STATES PATENT OFFICE.

GARTH G. GILPIN, OF RIVERSIDE, ILLINOIS, ASSIGNOR, BY MESNE ASSIGNMENTS, TO UNION METAL PRODUCTS COMPANY, OF CHICAGO, ILLINOIS, A CORPORATION OF DELAWARE.

UNCOUPLING DEVICE FOR CAR COUPLERS.

Application filed April 4, 1921. Serial No. 458,501.

To all whom it may concern:

Be it known that I, GARTH G. GILPIN, a citizen of the United States, residing at Riverside, in the county of Cook and State 5 of Illinois, have invented new and useful Improvements in Uncoupling Devices for Car Couplers, of which the following is a specification.

This invention relates to improvements in 10 uncoupling devices for car couplers and more particularly to devices of this character employed on freight cars, and usually known as release rigging.

It is the object of this invention to provide 15 a simple and efficient uncoupling device comprising but few parts and which can be readily attached to the different types of freight cars.

This particular invention relates to what 20 is generally known in this art as the push down type of uncoupling device and comprises two levers having their adjacent ends pivotally mounted on the same fulcrum. The particular advantage of this construction 25 resides in the manner in which the levers are pivoted upon the fulcrum. In levers of this general type mounted on a common fulcrum the connection between the levers must allow for the longitudinal movement 30 of the coupler head in draft and in buffing and the rotative movement of the pin lifting lever about the fulcrum must be limited for the purpose of safety to the operator.

The manner of mounting the levers on the 35 fulcrum, in accordance with this invention, provides at the fulcrum means allowing play of the free end of the pin lifting lever in a horizontal plane without transmitting such movement to the hand lever, the connection 40 between the levers surrounds the fulcrum and tilting of either lever from the vertical plane is prevented by positioning the levers between the shoulder on the fulcrum member and lugs (15) on the bearing and connecting block, or other similar projections 45 on the fulcrum parts. This elimination of the tilting of the levers considerably reduces the friction between the levers and their fulcrum, and safety stops preventing excessive 50 rotating movement of either lever are also arranged at the fulcrum.

Fig. 1 is a view in end elevation of a portion of a freight car illustrating the application of this invention.

Fig. 2 is a top plan view of the same. 55

Fig. 3 is an enlarged detail top plan view of the fulcrum and adjacent ends of the levers with parts broken away.

Fig. 4 is an enlarged view in end elevation of Fig. 3. 60

Fig. 5 is a view in section taken on the line 5—5 of Fig. 3 looking in the direction of the arrows.

In the embodiment of this invention as 65 illustrated the numeral 1 indicates the end of a freight car of the non-end sill type, 2 the striking casting, 3 the coupler head, 4 the coupler locking pin eye, 5 the side sill and 6 the brake mast, all of which are of usual construction. 70

The uncoupling device comprises an operating lever 7 and a pin lifting lever 8 having their adjacent ends mounted on a common fulcrum including a casting 9 mounted on a plate 10 depending from the underside 75 of the car end. The pin lifting lever is provided with an offset to pass the brake mast with its free end portion parallel to the car end, and is of reduced size, to pass through and beyond the eye of the locking pin with the extremity bent in the form of a hook. Both ends of both levers are preferably offset, as shown, so that their extremities will lie in parallel horizontal planes which will allow the coupler head 80 to move back and forth transversely without transmitting its movement to the pin lifting lever, provide a more convenient manner for attaching and mounting the adjacent ends of the levers on the fulcrum 85 and afford a ready hand grip or foot engagement on the free end of the operating lever. 90

The fulcrum casting 9 comprises a base plate having a hollow boss 11 extending at 95 right angles therefrom and is provided with a reduced cylindrical portion 12 at its outer end. Rectangular openings 13 are swedged in the adjacent ends of the operating and pin lifting levers through which is passed a 100 rectangular connecting and bearing block 14 having a central aperture adapted to pass over and rotate upon the reduced portion 12 of the fulcrum casting. This connecting and bearing block 14 is provided on the outside along its upper and lower edges with right angular lugs or projections 15 and the block is secured in position by a bolt 105

16 passing from the rear through the supporting plate 10 and parts 11 and 12 of the fulcrum casting having a washer 17 and nut 18 on the outer end of the fulcrum adapted to be engaged by the outer side of the bearing block.

A separate connecting member and bearing block has the advantage of increasing the bearing area on the journal fulcrum 10 thereby reducing the friction and making the device easier to operate and also reducing the wear on the associated parts. The connecting block non-rotatively connects the operating lever and the pin lifting lever so that a force exerted on the outer end of the operating lever raises the inner end of the pin lifting lever. It is preferable to arrange the hand operating lever on the inner side adjacent to the shoulder formed by the boss 11. To allow or compensate for longitudinal movement of the free end of the pin lifting lever, the end of this lever about the fulcrum is bent at an angle, as clearly shown in Fig. 3, so that the bend 19 in the metal is 25 vertical and passes through the center of the fulcrum. The lugs or projections 15 on the connecting bearing block may be tapered from the center of the fulcrum towards each end, however the thickest portion will be opposite the bend in the pin lifting lever so that movement back and forth in the direction of the longitudinal center of the car will cause this end of the lever to pivot on the bearing block projections without transmitting such movement to the operating lever. Since the bearing and connecting block is of rectangular shape and is received within similar rectangular openings in the ends of each of the levers a downward movement of the operating lever will cause a corresponding upward movement to the pin lifting lever for unlocking the coupler head.

To provide means for limiting the rotative movement about the fulcrum of the two levers it is preferable to provide a clutch contact between the enlarged boss 11 and the adjacent end of the bearing and connecting block 14, thereby allowing sufficient movement for the operation of the uncoupling device and prevent further movement of either lever in either direction. A limit to the upward movement of the pin lifting lever is desirable to protect the operator in the event of failure of parts within the coupler head and a limit to the downward movement of said pin lifting lever is desirable to support the coupler in case of a carry iron failure, and a limit to the downward movement of the operating lever is desirable to protect the operator in case of a broken connection between the pin lifting lever and the coupler or the pin lifting lever itself. The preferable construction as illustrated comprises similar extensions 20 on opposite sides of the bearing block and connecting

member entering in pockets 21 in the boss 11, whereby the shoulders 22 in the boss will limit the amount of rotation of the bearing block and connecting member about the fulcrum.

While this invention is illustrated as applied to a certain type of freight car, it is readily adapted with but slight immaterial changes for application to other types.

What I claim is:

1. A release rigging for railroad car couplers comprising an operating lever, a coupler lock pin lifting lever, a fulcrum for said levers upon the car, a combined connecting and bearing block which passes through apertures in said levers, and means limiting the rotative movement of said block. 80

2. A release rigging for railroad car couplers comprising an operating lever, a coupler lock pin lifting lever, a fulcrum for said levers upon the car, a combined connecting and bearing block which passes through apertures in said levers, means thereon allowing pivotal movement of the pin lifting lever thereon horizontally independent of the operating lever, and means limiting rotative movement of said block. 90

3. A release rigging for railroad car couplers comprising an operating lever, a coupler lock pin lifting lever, a fulcrum for said levers upon the car, a combined connecting and bearing block for said levers upon said fulcrum passing through apertures provided therefor in the adjacent ends of said levers, said block having lugs upon the upper and lower edges thereof adapted to hold said levers thereon, said apertured end of the pin lifting lever having a bend therein, said lugs tapered from center to ends coacting with said bent portion of the pin lifting lever to allow limited pivotal movement on said block about said lugs, and a clutch contact between said block and fulcrum limiting the rotative movement about the fulcrum. 100

4. An uncoupling device for car couplers comprising an operating lever, a coupler lock lifting lever, a fulcrum for said levers upon the car, a combined connecting and bearing block for said levers mounted upon said fulcrum, the fulcrum ends of said levers being positioned between projections on the said fulcrum and said bearing block respectively so as to prevent said levers tipping from their vertical cross sectional axis though permitting relative movement of said levers in a substantial horizontal plane, and extensions on the fulcrum and bearing member respectively so positioned as to limit the rotative movement of said levers about said fulcrum. 115

5. In a release rigging for car couplers comprising an operating lever having an aperture adjacent its fulcrum end, a coupler pin lifting lever having an aperture adja- 130

cent its fulcrum end, a member passing through said apertures having a non-rotative connection therewith, a fulcrum passing through said member having a rotative connection therewith, said levers mounted upon said member so as to retain the ends of said levers in a substantially vertical plane, said fulcrum having projections which engage projections on said member to limit the 10 rotative movement of said member about said fulcrum.

6. In a release rigging for car couplers comprising an operating lever having an aperture adjacent its fulcrum end, a coupler pin lifting lever having an aperture adjacent its fulcrum end, a member passing through said apertures having a non-rotative connection therewith, a fulcrum passing through said member having a rotative connection therewith, said levers mounted upon said member so as to permit relative horizontal movement between said levers, said levers mounted upon said member so as to retain the ends of said levers 25 in a substantially vertical plane.

7. An uncoupling device for car couplers comprising a fulcrum, an operating lever having a rectangular aperture adjacent its fulcrum end, a coupler pin lifting lever having a rectangular aperture adjacent its fulcrum end, and a rectangular connecting and bearing block passing through the apertures of said levers, said bearing block having rotative connection with said fulcrum, said bearing block arranged to retain the ends of said levers in a substantially vertical plane.

8. In a release rigging for car couplers comprising an operating lever having an aperture adjacent its fulcrum end, a coupler pin lifting lever having an aperture adjacent its fulcrum end, a member passing through said apertures having non-rotative connection therewith, and a fulcrum passing through said member having a rotative connection therewith, said levers mounted upon said member so as to retain the ends of said levers in a substantially vertical plane.

9. An uncoupling device for car couplers comprising an operating lever, a coupler pin lifting lever, a fulcrum for said levers, and a combined connecting member and bearing block having vertically positioned projections on its outer edge, said block passing through apertures in the adjacent ends of said levers, the fulcrum ends of said levers being positioned between the projections on the bearing block and the fulcrum so as to prevent said levers tipping from their vertical cross sectional axis.

60 10. In a release rigging for car couplers

comprising an operating lever having an aperture adjacent its fulcrum end, a coupler pin lifting lever having an aperture adjacent its fulcrum end, a member passing through said apertures having a non-rotative connection therewith, and a fulcrum passing through said member having a rotative connection therewith, said fulcrum having projections which engage projections on said member to limit the rotative movement 70 of said member about said fulcrum.

11. In a release rigging for car couplers comprising an operating lever having an aperture adjacent its fulcrum end, a coupler pin lifting lever having an aperture adjacent its fulcrum end, a member passing through said apertures having a non-rotative connection therewith, and a fulcrum passing through said member having a rotative connection therewith, the fulcrum ends 80 of said levers being positioned between projections on said member and projections on said fulcrum so as to retain said levers in substantially a vertical plane though permitting relative movement between said 85 levers in a horizontal plane.

12. In a release rigging for car couplers comprising an operating lever having an aperture adjacent its fulcrum end, a coupler pin lifting lever having an aperture adjacent 90 its fulcrum end, a member passing through said aperture having a non-rotative connection therewith, a fulcrum passing through said member having a rotative connection therewith, said levers mounted upon 95 said member so as to permit relative horizontal movement between said levers, said fulcrum having projections which engage projections on said member to limit the rotative movement of said member about said 100 fulcrum.

13. In a release rigging for car couplers comprising an operating lever having an aperture adjacent its fulcrum end, a coupler pin lifting lever having an aperture adjacent its fulcrum end, a member passing through said apertures having a non-rotative connection therewith, a fulcrum passing through said member having a rotative connection therewith, said levers mounted 105 upon said member so as to permit relative horizontal movement between said levers and so as to retain the ends of said levers in a substantially vertical plane, said fulcrum having projections which engage projections on said member to limit the rotative movement of said member about said fulcrum.

GARTH G. GILPIN.
